US0D1029840S

(12) **United States Design Patent** (10) **Patent No.:** **US D1,029,840 S**
(45) **Date of Patent:** **** Jun. 4, 2024**

(54) **TEACH PENDANT BUMPER**

(71) Applicant: **ROBOWORLD MOLDED PRODUCTS, LLC**, Mason, OH (US)

(72) Inventor: **Christian A. Tur**, Mason, OH (US)

(73) Assignee: **Roboworld Molded Products, LLC**, Mason, OH (US)

(**) Term: **15 Years**

(21) Appl. No.: **29/835,588**

(22) Filed: **Apr. 20, 2022**

(51) LOC (14) Cl. **14-02**

(52) U.S. Cl.

USPC **D14/440**

(58) **Field of Classification Search**

USPC D14/217, 250-253, 401, 425, 440, 447, D14/454; D10/74, 70; D3/218;

D21/333

(57) **CLAIM**

The ornamental design for a teach pendant bumper, as shown and described.

DESCRIPTION

FIG. 1 is a perspective view of a teach pendant bumper; FIG. 2 is a front side elevational view of the teach pendant bumper;

FIG. 3 is a rear side elevational view of the teach pendant bumper;

FIG. 4 is a left side elevational view of the teach pendant bumper;

FIG. 5 is a right side elevational view of the teach pendant bumper;

FIG. 6 is a top plan view of the teach pendant bumper; and, FIG. 7 is a bottom plan view of the teach pendant bumper. Broken lines illustrate portions of the teach pendant bumper that form no part of the claimed design.

1 Claim, 7 Drawing Sheets
